UNITED STATES PATENT OFFICE.

JAMES RANKIN GARROW, OF WIMBLEDON, LONDON, ENGLAND.

PROCESS FOR THE LOW AND MEDIUM TEMPERATURE CARBONIZATION OF COAL, OIL SHALE, WOOD, PEAT, AND THE LIKE.

Application filed April 30, 1921, Serial No. 465,712, and in Great Britain July 31, 1918.

(GRANTED UNDER THE PROVISIONS OF THE ACT OF MARCH 3, 1921, 41 STAT. L., 1213.)

This invention relates to an improved process and apparatus for the carbonization or destructive distillation of coals, oil shale, wood, peat and the like by the so-called low and medium temperature processes whereby an increased yield of by-products such as oils of the paraffin series, ammonia and gas pyroligneous acids etc., can be obtained, in conjunction with a simplification of the plant and a more economical utilization of the fuel.

It is well known that in the carbonizing of coal etc., by the method known as the low temperature process as usually carried out, the temperatures employed range from about 450° to about 600° centigrade and that in the so called medium temperature carbonizing process the temperatures employed are from about 600° to about 1000° C. It is also well known, that the oils obtained under the first mentioned process are principally of the paraffin series, while in the second or medium temperature process the oils obtained are partly of the paraffin series and partly of the benzene series. The yields and proportions depend to a large extent upon the nature of the coals or shale treated.

The retorts commonly used in the low temperature process are externally fired and owing to the low heat conductivity of coal under the lower temperatures are generally made only 4 inches to 6 inches internal diameter. It will be clear that a great number of such small retorts are required for a carbonizing plant of a commercial size the great number of these retorts necessarily complicating the plant and preventing the utilization of the fuel to the fullest extent possible.

In the medium temperature carbonizing process as usually carried out, the conditions ruling are more favorable for the transmission of heat owing to the higher temperature differences between the externally fired retort wall and the coals to be carbonized, consequently the retorts are made of greater transverse dimensions than the former and therefore carbonize a greater quantity of coal in the same number of hours but the yield of oils of the paraffin

series is low compared with the yield obtained under the low temperature carbonizing process.

In both cases the retorts are usually heated externally and being made of a more or less refractory material of a low thermal conductivity the amount of fuel used is many times greater than the theoretical amount required to raise the coal or shale to the carbonizing temperature.

By way of example:—

10-15% of the weight of coal carbonized is generally used as fuel in the modern regenerative furnaces and retort setting, while in other settings of the non-regenerative type twice the above stated amount is frequently necessary.

In my improved process the carbonizing or decomposition of the coal or shale etc., is achieved by means of a hot gas being caused to travel inside the retort and this gas being in direct contact with the coal or shale etc., to be treated without any intervening wall the heat transmission is far more effective and rapid than by any other method. It is also clear that the driving off of volatile matters, is greatly facilitated.

If the temperature of one ton of coal or shale having a specific heat of 0.32 has to be raised from 15° to 600° centigrade, 187200 kilogram calories are required, corresponding to 25 kilograms of coal at 750 kilogram calories exclusive of the amount of coal required to evaporate the moisture contained in the coal, generally 1.5 kilograms of coal being required per 1% moisture per ton of coal.

It will be seen from the above that the theoretical figure is only 2.5% to 3% compared with the 10% to 15% used in the external heating processes commonly in use.

According to the present invention the hot gases which are employed as the heating medium are obtained by arranging one or more gas producers of any well known type in close proximity to a rotary retort or retorts through which the carbonaceous material to be distilled is passed in a continuous manner, and the requisite quantity of the gas which is evolved during the treatment of the material within the producer

or producers and which is required to heat the material within the retort or retorts is withdrawn under control directly from the producers and passed without ignition or combustion through the interior of the retort or retorts in contact with the material contained therein, whereby the so-called sensible heat of the producer gas, which heat would otherwise be wasted, is utilized to produce distillation of the carbonaceous material. In addition to internal heating in the manner described the retort can also be heated externally but it is preferred to insulate the retort externally and to rely on internal heating. It is important to note that the producer gas is not ignited before being passed into the retorts and that only its sensible heat is utilized to distil the carbonaceous material within the retort, as by working the retorts in the manner above described the fuel consumption is lowered and approaches the theoretical limit, while a large volume of combined producer and retort gas of great heating value can afterwards be recovered as well as a greatly increased yield of oils, ammonia, etc. The amount of carbonaceous residuum produced corresponds closely to the amount produced by any well known carbonizing process.

When the process is applied to the distillation of wood, peat, etc., the appropriate by-products are also obtainable in the most advantageous manner.

In order that the said invention may be clearly understood and readily carried into effect, the same will now be described more fully with reference to the accompanying drawing which illustrates diagrammatically the layout of a plant constructed according to the present invention and in which:

A is a hopper or container for the raw material B, which is fed into the retort or rotary drum C. a is a pipe by means of which the raw material is fed from the hopper A into the retort C, the pipe a also serving to conduct the mixed producer and retort gases away from the retort C. c is a fixed annular casing surrounding one end of the retort and wherein the fuel which is treated in the retort is collected after falling through the opening c'. c' is the fuel off-take or discharge valve from the retort C. E is the producer, the producer gas from which is employed for treating the material undergoing distillation in the retort C. e is a pipe through which the producer gas is drawn from the producer and fed into the retort C. e' is a valve for controlling the quantity of producer gas supplied to the retort C. F is a condenser for the mixed gases which leave the retort C, and G is an absorption apparatus for the recovery from said mixed gases of condensable and absorbable hydro-carbon products contained therein. The pipe i conducts the stripped

gases from the absorption apparatus G to an ammonia absorber I.

In the case of moist materials, such as peat, or in cases where it is considered desirable to subject other carbonaceous materials to a preliminary heating or drying treatment, part of the supply of producer gas may be withdrawn under control from the producer and passed directly through a receptacle containing the material which is to be dried or heated, the sensible heat of the producer gas being thereby utilized to dry the material before it passes into the retort the other part of the supply of producer gas being withdrawn as before (for example by means of a fan) from the producer and passed under control through the retort in which the carbonaceous material from the aforesaid receptacle is subsequently distilled or carbonized. The process of treating carbonaceous material by means of the sensible heat of producer gas is thus divided into two stages i. e., a preliminary drying operation and a subsequent distilling or carbonizing operation each stage being carried on by means of a separate supply of producer gas. The producer gas after it leaves the aforesaid receptacle may be mixed for further utilization with the combined producer and retort gas which leaves the retort after the hydrocarbon oils have been removed therefrom. The aforesaid receptacle may conveniently be situated in close proximity to the retort and the material after being dried may be adapted to be fed directly into the retort, so as to render the process continuous.

What I claim and desire to secure by Letters Patent of the United States is:

A method of producing in liquid form and at low temperatures from carbonaceous materials hydro-carbon oils, together with the production or recovery of a large volume of gas suitable for illuminating or power purposes, which consists in passing in a continuous manner through a rotating retort the carbonaceous materials which are to be distilled, withdrawing a controlled volume of producer gas at a temperature not exceeding 600° C. from an adjacent producer and passing the heated gas without previous ignition and in the form of a continuously flowing stream through the retort in counterflow to the carbonaceous materials passing therethrough so that the sensible heat of the gas is utilized for the purpose of effecting distillation, in withdrawing the combined retort and producer gases thus formed to condensing means so as to recover in liquid form from the retort gases the hydrocarbon oils contained therein, and in conducting away the combined retort and producer gas from the condensing means for combustion elsewhere.

JAMES RANKIN GARROW.
